UNITED STATES PATENT OFFICE.

WILLIAM LAYTON AND COZ R. LOWE, OF CHICAGO, ILLINOIS, ASSIGNEES TO GARRETT GO-CART & CARRIAGE COMPANY, OF CHICAGO, ILLINOIS, A CORPORATION OF ILLINOIS.

CHILD'S FOLDING CARRIAGE.

1,109,848.

Specification of Letters Patent.

Patented Sept. 8, 1914.

Application filed June 10, 1912. Serial No. 702,713.

To all whom it may concern:

Be it known that we, WILLIAM LAYTON and Coz R. LOWE, citizens of the United States, residing at Chicago, in the county 5 of Cook and State of Illinois, have invented certain new and useful Improvements in Children's Folding Carriages, of which the following is a specification.

The object of this invention is to produce a child's carriage that shall be light and simple in construction, which shall be strong and rigid and which shall be capable of being folded or unfolded with the least possible effort and attention.

With carriages of previous forms it has been difficult or impossible for the operator to fold or unfold the carriage while supporting the child upon the arm. It is a special object of this invention to construct 20 a child's carriage in such a manner that it may be readily operated without stooping, and with one hand, leaving the other free to support the child.

In the accompanying drawings, Figure 25 1 is a side elevation of one form of carriage embodying the features of our invention, the carriage being shown in its unfolded or erected condition. Fig. 2 is a fragmental rear view. Fig. 2^a is a detail view of a 30 locking means. Fig. 3 is a front end view of said carriage. Fig. 4 is a side elevation of the carriage when partly unfolded. Fig. 5 is a side view of the carriage when completely folded. Fig. 6 is an underside view 35 of the completely folded carriage. Fig. 7 is a fragmental vertical section on line 7 7 of Fig. 1.

The embodiment which has been selected in order to illustrate the invention comprises a rigid substantially rectangular bed frame consisting of the side bars 1 and 2 the rear cross bar 3 (Fig. 2) and the front cross bar 4, said bars being rigidly secured together. If desired, the front cross bar 45 may be integral with the two side bars, as herein shown. Two brackets 5 and 6 are fixed to and extend downwardly from the rear corners of the bed frame, and two other brackets 7 and 8 are attached to and extend 50 downwardly from the side bars 1 and 2 at points forward of the brackets 5 and 6. To the brackets 5 and 7 is pivoted a wheel-supporting bow 9, and to the brackets 6 and 8 is pivoted a similar bow 10.

The wheels 11 are mounted upon short axles 55 carried by these bows.

While the body of the carriage may be of any suitable construction, we have herein shown the seat as attached to two spring bars 13, the forward ends of which bars 60 are secured to a cross-bar 14 (Figs. 6 and 7) fixed to the brackets 7 and 8. The back 15 is pivoted at its lower edge to lugs 16 on the rear ends of the seat-supporting bars 13. (See Fig. 4).

17 indicates a foot-rest which may be of any preferred or ordinary construction. The side arms of the handle 18 are herein shown as pivoted at 19 on the side bars 1 and 2. The sides of the carriage body may be of 70 any desired construction; they are herein shown as comprising two rails 20 pivoted at their rear ends to plates 21 fixed to the handle, and at their forward ends to arms 22 which are pivoted to lugs 23 fixed to and 75 projecting downwardly from the side bars 1 and 2. The flexible side walls 24 are fixed to the rails 20 and the arms 22. These walls are omitted from Figs. 4, 5 and 6 for the sake of clearness. If 80 desired, a rod 25 may be pivoted to the arm 22 and the handle at each side of the carriage to assist in preventing displacement of clothing, cushions or other articles placed upon the seat 12. In order 85 to hold the body in erected condition there may be provided suitable means, such as the jointed braces 26 extending between the handle and the rails 20. The back 15 may be adjustably supported in any desired manner, as by means of a bail 27 pivoted to the plates 21 and extending behind the back. The bail 27 extends freely 90 through a rigid strap or loop 28 fixed to the rear side of the back.

If desired, a hood or top of any preferred form may be provided. Herein we have shown a hood 29 which is pivoted to lugs 30 carried by the rails 20.

The body of the carriage may be collapsed 100 or folded in the following manner: The back 15 is placed in its normal or substantially upright position, as shown in Fig. 3. The hood is folded and swung rearwardly until it rests upon the side arms of the bail 105 27. The jointed braces 26 are flexed upwardly slightly. The handle-bars may now be swung forwardly, thus causing the back

to lie flat upon the seat, the rails 20 extending substantially parallel with and close to the side bars 1 and 2, and the hood lying flat upon the back. In practice, the body will not usually be folded by a separate operation, as just described, but will be folded during the general operation of folding the carriage, which mode of operation will be described hereinafter.

10 The wheel-supporting bows 9 and 10 are arranged to be folded by an operation separate from that necessary in folding the body, but are preferably arranged to be unfolded practically simultaneously with the unfolding 15 of the body. The rear ends of the bows are locked in their erected or unfolded position by means of a bail 31 (Fig. 2) which is pivoted to lugs 32 on the brackets 5 and 6, the side arms of said bail being arranged to 20 enter locking hooks 33 fixed to the bows. When said bail is in engagement with the hooks the bows are locked against swinging movement. The wheel-supporting bows are arranged to be swung into and out of their 25 operative position by means of a bail 34 which is pivoted to the lugs 23. One side arm of the bail 34 extends through a rigid loop 35 fixed to the bow 10. On the bow 9 is fixed a bracket 36 and to said bracket is 30 affixed a rigid loop 37 through which the adjacent side arm of the bail 34 extends. The loop 37 is located in a higher horizontal plane than the loop 35 by reason of the fact that the former is mounted upon the bracket 36. When the bail 34 is swung rearwardly 35 it engages first the lower loop 35 and then the upper loop 37, and thereby draws the bows 9 and 10 inwardly into their folded position, the bow 10 moving first so as to 40 pass and avoid interference with the bow 9.

The wheel-locking bail 31 and the wheel-folding bail 34 are connected together for simultaneous swinging movement in opposite directions. Herein we have shown for 45 this purpose two bars 38 and 39 pivoted to the upper ends of the side arms of the bail 34 and connected by links 40 to the side arms of the bail 31. The rear ends of the bars 38 and 39 are united by means of the 50 cross-bar 41, which may, if desired, be integral with said bars, the parts 38, 39 and 41 thus forming a U-shape member. The bars 38 and 39 extend longitudinally of the bed frame and to a point rearward of the 55 rear wheels.

In order that the entire carriage may be unfolded by a single movement or effort on the part of the operator, the arms 22 are extended downwardly and are connected by 60 a cross-portion 42 which may, if desired, be integral with said arms. The arms 22 and cross-portion 42 thus form a U-shape bail. Said cross-portion normally lies directly behind the side arms of the wheel-folding 65 bail 34. It will be seen that when the joint-

ed braces 26 are in their normal position, the cross-portion 42 will be secured against movement, and the bails 31 and 34 will be locked in place. Said jointed braces thus serve to lock the entire carriage in its operative condition.

When the carriage is to be folded, the back is placed in the normal or upright position, the hood is folded and laid back against the bail 27, and the jointed braces 75 26 are flexed upwardly off dead-center. If the carriage is occupied, the operator removes the child and, if necessary, supports the child upon her left arm. Then, while holding the handle 18 with her right hand, 80 the operator places her foot upon the cross-bar 41 and depresses said cross-bar. The bed frame of the carriage is thereby caused to tilt upwardly on the axis of the rear wheels until the cross-bar 41 rests upon the 85 ground. By reason of such upward tilting movement of the bed frame, the bed frame and the handle have approached one another, thus causing the body to be partially folded. The rising of the bed frame has also brought 90 the front cross-bar 4 within convenient reach of the right hand of the operator. The operator, by taking hold of the front cross-bar 4 with her right hand and drawing said cross-bar toward herself, may now swing 95 the bed frame into an upright position, as shown in Fig. 4, thereby completely collapsing the body of the carriage and raising the rear wheels off the ground. The operator may now fold the wheels without stooping 100 and with little effort by merely pressing downwardly upon the cross-bar 4. Such pressure will cause relative movement between the bars 38 and 39 and the rest of the carriage, the latter moving downwardly 105 and thereby causing the locking bail 31 to swing out of the hooks 33, and the wheel-folding bail 34 to engage the loops 35 and 37 and swing the wheels into folded position, as shown in Fig. 5. The carriage is 110 now completely folded, and may be carried in such condition, the front cross-bar 4 serving as a handle. It will be understood that the relative movement just described between the bars 38 and 39 and the rest of the carriage is largely caused by the weight of the parts, the operator applying only sufficient force to overcome the friction. The operation of erecting the carriage is as follows: Assuming the carriage to be in the position 115 shown in Fig. 5, the operator grasps the handle and lifts the carriage off the ground. When the carriage is thus lifted, the bed frame swings downwardly by reason of its weight and the weight of the attached parts, into its operative position. In such movement, the arms 22 likewise assume their normal position, the cross-portion 42 pressing 120 against the wheel-folding bail 34 and causing said bail to spread the bows 9 and 10 125 130

apart into their normal position. Such movement of the bail 34 causes the locking bail 31 to move into its operative position, because said bails are connected together through the bars 38 and 39 and the links 40. The locking of the erected carriage may now be completed by straightening the jointed braces 26 into their normal position, as shown in Fig. 1.

10 It will be seen that the carriage may be folded and unfolded with one hand, and without stooping, the other hand being free for use in supporting the child, if necessary.

We claim as our invention:

15 1. In a folding carriage, a bed frame, front and rear wheels supporting said bed frame, a handle connected to the rear portion of the bed frame and adapted to fold forwardly against the bed frame, and means projecting rearwardly from the bed frame 20 upon which the operator may exert downward pressure to tilt the bed frame upwardly upon the axis of the rear wheels to bring the handle and the bed frame into 25 proximity to each other, said means being free from positive connection with the handle, whereby the latter may swing toward the bed frame independently of said means.

30 2. In a folding carriage, in combination, a foldable body, wheel-supporting members foldable separately from the body, foot-pressure-receiving means extending rearwardly of the wheels and connected to the body for tilting the latter and a handle 35 connected to the body and free from positive connection with the foot-pressure-receiving means.

3. In a folding carriage, in combination, a carriage frame; wheels connected to said 40 frame for folding and unfolding movement; a bail pivoted to the frame for folding and unfolding the wheels; a second bail pivoted between its ends to the frame, the lower portion of the second bail extending alongside 45 the first bail; a handle pivoted to the frame; and carriage-body rails connecting the handle to the upper portion of the second bail.

4. In a folding carriage, in combination, a carriage frame, wheels connected to said 50 frame for folding and unfolding movement, a wheel-folding member pivoted to the frame, and an actuator connected to said wheel-folding member adapted to rest upon the ground and receive the weight of said carriage frame and wheels.

5. In a folding carriage, in combination, a carriage frame; wheels connected to said 60 frame for folding and unfolding movement; a wheel-operating member pivoted to the frame; and an actuator connected to said member arranged for movement longitudinally of the carriage frame said actuator extending rearwardly beyond the rear wheels.

6. In a folding carriage, in combination, a carriage frame; front and rear wheels con-

nected to said frame for folding and unfolding movement; a wheel-operating member; and an actuator for said member arranged for movement longitudinally of the carriage frame, said actuator extending 70 rearwardly to a point beyond the rear wheels.

7. In a folding carriage, in combination, a foldable body; wheel-supporting members foldable separately from the body; foot-pressure-receiving means extending rearwardly of the wheels and connected to the body for tilting the latter; and a member for operating said wheel-supporting members, said operating member being actuated 80 by said foot-pressure-receiving means.

8. In a folding carriage, the combination of a wheel-supported body; body-tilting means extending rearwardly from the body into position to receive the pressure of the operator's foot; and wheel-operating means arranged for actuation by said body-tilting means.

9. In a folding carriage, in combination, a carriage frame; wheels connected to said carriage for folding and unfolding movement; a wheel-operating member pivoted to said carriage frame; a wheel-locking member pivoted at one end to said carriage frame; and an actuating member connected to said wheel-operating member and said wheel-locking member and extending longitudinally of the carriage frame, and adapted to actuate simultaneously, but in opposite directions, said other members.

10. In a folding carriage, in combination, a carriage frame; wheels connected to said frame for folding and unfolding movement; a wheel-operating bail and a wheel-locking bail pivoted to said carriage frame; and a U-shaped member connected to said bails and extending longitudinally of said frame for swinging said bails.

11. In a folding carriage, in combination, a carriage frame; wheels connected to said frame for folding and unfolding movement; a wheel-operating bail and a wheel-locking bail pivoted to said carriage frame; and a U-shaped member for swinging said bails, said member extending rearwardly to a point beyond the rear wheels so as to rest upon the ground when the carriage frame is placed in an upright position.

12. In a folding carriage, in combination, a carriage frame; wheels connected to said frame for folding and unfolding movement; a wheel-operating bail the side arms of which are pivoted intermediate their ends to said carriage frame; a wheel-locking bail the side arms of which are pivoted at their upper ends to the carriage frame; and an actuating member pivoted to the upper ends of the side arms of said wheel-operating bail and having a link connection with the side arms of said wheel-locking bail, said actuat-

ing member extending to a point rearward of the carriage frame.

13. In a folding carriage, the combination of a bed frame; two wheel-supporting bows pivoted to said bed frame; a handle pivoted to the rear end of said bed frame; rails connected at their rear ends to said handle; arms pivoted intermediate their ends to the bed frame and connected at their upper ends to said rails, the lower ends of said arms being united by a cross portion; and a bow-swinging member pivoted to said bed frame, said cross-portion lying at one side of said bow-operating member for swinging said bow-operating member in one direction.

14. In a folding carriage, the combination of a bed frame; two wheel-supporting bows pivoted to said bed frame; a handle pivoted to the rear end of said bed frame; rails connected at their rear ends to said handle; arms pivoted intermediate their ends to the bed frame and connected at their upper ends to said rails, the lower ends of said arms being united by a cross-portion; a bow-swinging member pivoted to said bed frame, said cross-portion lying at one side of said bow-operating member for swinging said bow-swinging member in one direction; a bow-locking member pivoted to said bed frame; an actuating member connected to said bow-swinging member and said bow-locking member, said member extending longitudinally of the bed frame to a point beyond the rear wheels; a seat connected to the bed frame; a back pivoted to the rear portion of the seat; and a member connected to the handle for supporting said back.

15. In a folding carriage, in combination, a carriage frame; two pairs of wheels connected to the frame for folding and unfolding movement; a bail pivoted between its ends to the frame, the lower portion of the bail being adapted to swing into the space between the pairs of wheels and thus spread the pairs of wheels apart; and a U-shaped member connected to the upper end of the bail and extending longitudinally of and below the frame for swinging said bail.

16. In a folding carriage, in combination, a carriage frame; two pairs of wheels connected to the frame for folding and unfolding movement; a bail pivoted between its ends to the frame, the lower portion of the bail being adapted to swing into the space between the pairs of wheels and thus spread the pairs of wheels apart; and a U-shaped member connected to the upper end of the bail and extending longitudinally of and below the frame for swinging said bail, said member extending rearwardly to a point beyond the rear wheels so as to rest upon the ground when the carriage frame is placed in an upright position.

In testimony whereof we hereunto affix our signatures in the presence of two witnesses.
